ASH DISPOSAL APPARATUS FOR STOKERS

Clark Scholl, Springfield, Ohio, assignor to The Steel Products Engineering Company, Springfield, Ohio, a corporation of Ohio

Application March 12, 1948, Serial No. 14,539

8 Claims. (Cl. 226—27)

1

This invention relates to portable ash containers for use in an ash removal system of a domestic heating furnace to receive the ashes from an ash conveyor of the worm feed type.

One of the principal objects of the invention is to provide such an ash container which has a valve controlled opening in the bottom thereof for receiving ashes from the conveyor and which is so constructed with relation to the supporting mount therefor on the conveyor that it cannot be removed except when the ash receiving opening therein is fully closed.

Another object is to provide such an ash container wherein the valve controlling the ash receiving opening is positioned below the bottom of the container for rotational movement on a supporting portion of the container which is constructed to avoid pockets or channels wherein ashes might accumulate and interfere with the proper operation of the valve.

An additional object is to provide such an ash container and supporting mount therefor on the ash conveyor which have interlocking parts for holding the container in ash receiving position on the conveyor except when the ash receiving opening at the bottom of the container is fully closed, and thus preventing spilling of ashes when the container is removed for dumping purposes.

It is also an object of the invention to provide an ash container wherein the valve which controls the ash receiving opening in the bottom of the container and the supporting mount for the container on the conveyor have cooperating parts indexing the opening in the valve with the discharge opening in the conveyor and wherein the remainder of the conveyor is supported for rotation with respect to the valve and supporting mount to bring the ash receiving opening therein into and out of register with the discharge opening of the conveyor.

Other objects and advantages of the invention will be apparent from the following description, the accompanying drawings and the appended claims.

In the drawings—

Fig. 1 is an exploded view in perspective of an ash container in accordance with the invention and the supporting mount therefor on an ash conveyor;

Fig. 2 is a view partly in side elevation and partly broken away and in vertical section on the line 2—2 of Fig. 3 showing the ash container mounted on an ash conveyor in position to receive ashes therefrom;

2

Fig. 3 is a view of the container approximately on the line 3—3 of Fig. 2 with parts broken away at different levels to illustrate details of internal construction and arrangement;

Fig. 4 is a fragmentary view in vertical section on the line 4—4 of Fig. 5 showing the relative positions of the container and the supporting mount therefor while the container is being removed from or mounted on the conveyor;

Fig. 5 is a view taken approximately on the line 3—3 of Fig. 2 but with the parts in the relative positions shown in Fig. 4;

Fig. 6 is a fragmentary sectional view on a larger scale taken on the same section line as Fig. 2; and

Fig. 7 is a fragmentary sectional view on the line 7—7 of Fig. 3 and on the same scale as Fig. 6.

The drawings illustrate a preferred embodiment of the present invention in connection with

20 an ash remover stoker of the general type shown in Burton Patent No. 2,069,940, assigned to the same assignee as this application. As shown, a conveyor tube 10 is provided for conveying the solid fuel to the combustion zone, where it is burned in a suitable retort, not shown, and the conveyor 11 removes the ashes from the combustion zone. The conveyor 11 is provided with a discharge opening 12 in the upper part thereof, and a short discharge or outlet tube 13 is secured 25 to the conveyor to transmit ashes upwardly from the discharge opening 12. As shown in Fig. 3, the ash conveyor worm 15 is provided with a reversed flight portion 16, the two flights 15 and 16 terminating below the discharge opening 12 and cooperating to cause the ashes to be lifted upwardly through this opening and through the tube 13.

The container 20 is adapted for removable mounting on the ash conveyor 11 to receive the ashes from tube 13, this container being portable to facilitate ready carrying away and dumping of ashes. It is provided with a suitable top 21 sealed against a gasket 22 to prevent scattering of ashes therefrom. A carrying bail or handle 23 is secured to the container as shown in Figs. 1 and 2. The bottom 25 of the container 20 is provided with an eccentric ash receiving opening 26 which is disposed wholly to one side of the central axis 27 of the container.

50 A funnel 30 of sheet metal in the form of a hollow truncated cone is mounted within the container 20 with its lower end in register with the ash receiving opening 26, the funnel being secured to the container bottom 25 by a suitable flange 31. This funnel acts in use to receive

ashes from the discharge opening 12 and outlet tube 13 of the ash conveyor 11, and its smooth expanding inner surface guides the ashes upwardly substantially without tumbling or churning until they overflow the top of the funnel and fall into the interior of the container, reference being made in this connection to the co-pending application of Joseph E. McAdams, Serial No. 723,811, filed January 23, 1947, now Patent No. 2,509,872, issued May 30, 1950, and assigned to the same assignee as this application.

A valve 33 in the form of a circular plate is rotatably mounted below the container bottom for rotation relative thereto about the central axis 27, and this valve is provided with an eccentric opening 34 therethrough which is disposed wholly to one side of axis 27 and is thus adapted to be brought into and out of register with the ash receiving opening 26 in the bottom of the container. A narrow annular collar 35 is welded or otherwise secured to the under side of valve 33 in concentric relation with the opening 34 to form a pilot adapted to be received over the ash conveyor outlet tube 13. The valve 33 is rotatably supported on a flat ring 36 by overlapping its outer periphery with the inner periphery of such ring which is secured in spaced relation to the bottom 25 of the container by means of spacers 37, four of these spacers being shown. The spacers 37 and the ring 36 are all secured together and to the bottom plate 25 of the container as by spot welding or other suitable means to form a track for valve 33, the inner surfaces 38 of the spacers being cylindrically curved to guide the rotational movement of the valve.

In order to receive the container 20 on the ash conveyor 11, a flange 40 is welded or otherwise secured to the tube 13, this flange being disposed below the top of the tube to leave a projecting pilot portion 41 of the tube (Fig. 4). At opposite sides of the flange 40 are two projections 42, which are secured to the upper surface of the flange by means of spacers 43 and the sides 44 of which are tapered toward the center of the container (Figs. 1, 3 and 5). These projections 42 are adapted to be received through two corresponding oppositely located notches 45 in the outer periphery of the ring 36, so that the notches in the ring can be received over projections 42 and the outer periphery of ring 36 then rotated under projections 42 and in the groove 46 formed between ring 36 and the under surface of the bottom 25 of the container, thus releasably locking the container on the flange 40. Up-turned portions 47 are provided on the periphery of flange 40 between the projections 42 to aid in guiding and centering the container for rotation on the flange.

With this construction, it will be seen that the container can be mounted on or removed from the flange 40 only when the notches 45 in the ring 36 are in line with the projections 42. In addition, the valve 33 cooperates with parts of the conveyor and flange to prevent removal of the container except when the valve is in position fully closing the ash receiving opening 26. For this purpose a rib-like projection 50 (Figs. 1 and 7) is secured to the under side of valve 33 at a position on the opposite side of center from the opening 34 therethrough, and this rib 50 is adapted to engage between two similar spaced projections 51 in the form of bars secured to the upper surface of the mounting flange 40. These

parts thus cooperate to key the valve into a position wherein its opening 34 will receive the upwardly projecting pilot portion 41 of the discharge tube 13, and when the container and valve are thus properly mounted on the conveyor, this pilot portion of the tube and the projections 50 and 51 serve to locate and hold the valve against rotation with respect to the conveyor, leaving the container free to rotate relative to the valve in order to bring its ash receiving opening 26 into register with the tube 13.

Means are also provided for defining two limit positions of the rotational movement of the container in which its ash receiving opening is respectively fully closed by valve 33 and fully opened into register with the discharge tube 13. Referring to Figs. 1, 3 and 5, the spacer 37 which is opposite funnel 30 includes an outward projection 55 adapted to abut the tapered sides 44 of the projections 42. Fig. 5 shows the parts in one limit position of rotational movement of the container wherein the container can be mounted on or removed from the flange 50. As shown, the projection 55 is in contact with the projection 42 at the side of flange 40 on the opposite side of center from the tube 13. In this position, the ash receiving opening 26 is fully closed by valve 33 and the notches 45 line up with the projections 42, thus permitting the container to be moved vertically with respect to the conveyor as shown in Fig. 4. Fig. 3 shows the container as having been fully rotated from the position shown in Fig. 5 to the position in which the projection 55 on the spacer 37 opposite funnel 30 abuts the projection 42 adjacent the tube 13, and in this position of the parts the ash receiving opening 26 and funnel 30 are fully opened and in register with the tube 13.

In the operation of this device, when the container 20 is first to be mounted on the conveyor, the parts are in the relative angular positions shown in Figs. 1, 4 and 5, with the valve 33 being properly positioned for registry of its opening 34 and the pilot portion 41 of the discharge tube 13 but with the ash receiving opening 26 fully closed. The container is then positioned on the flange 40, the projection 50 on the valve 33 being received between the projections 51 on the flange 40, and the projections 42 being received through the notches 45 on the ring 36. The container 20 is then rotated in a counter-clockwise direction as viewed in Fig. 5, causing spacers 37 and ring 36 to rotate also while valve 33 remains in fixed non-rotating relation by reason of the interlocking engagement of rib 50 between bars 51. After approximately half a revolution, the parts are in the position shown in Fig. 3 wherein the projection 55 abuts the projection 42 adjacent the tube 13. In this position the ash receiving opening and funnel are fully opened to receive the ashes forced upwardly by conveyor 15, and the projections 42 and ring 36 interlock to hold the container in place so that it cannot be removed.

When it is desired to remove the container for dumping the ashes collected therein, the container must be rotated in a clockwise direction as viewed in Figs. 3 and 5 to the position shown in Fig. 3 wherein the projection 55 abuts the projection 42 opposite the tube 13, such abutting engagement of projection 55 with the respective projections 42 thus establishing limiting stops at the opposite ends of the range of movement of the container. In this position the notches 45 are again brought into register with

the projections 42, and then and only then can the container be removed from the conveyor. Since this rotational movement effects closing of the ash receiving opening and the bottom of the funnel by the valve 33, it will be seen that it is only when the ash receiving opening is thus fully closed that the container can be removed from the conveyor, the interlocking relation of projections 42 and ring 36 preventing such removal in all other relative angular positions of the container and flange 40. After the container is removed, it is dumped by removing its top 24, thus discharging both the ashes which are still in funnel 30 as well as those within the remainder of the container.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. Ash receiving apparatus comprising an ash conveyor having a discharge opening in the upper part thereof, a container having an ash receiving opening in the bottom thereof of substantially the same dimensions as said discharge opening, a valve supported by said container for movement relative thereto between positions respectively opening and closing said ash receiving opening, means for mounting said container above said conveyor to receive ashes through said ash receiving opening from said discharge opening, said container and said mounting means having releasably interlocking portions for releasably securing said container on said mounting means, and said valve and said mounting means having cooperating portions arranged in predetermined aligned relation with said interlocking portions of said container and said mounting means to prevent removal of said container from said mounting means except when said valve is in said position closing said ash receiving opening.

2. Ash receiving apparatus for use with an ash conveyor having a discharge opening in the upper part thereof, comprising a container having an ash receiving opening in the bottom thereof of substantially the same dimensions as said discharge opening, a valve movably secured to said container below the bottom thereof for movement relative thereto between positions respectively opening and closing said ash receiving opening, means for mounting said container above said conveyor to receive ashes through said ash receiving opening from said discharge opening, cooperating means on said valve and said mounting means for locating and holding said valve in predetermined position out of the path of ashes discharged from said discharge opening leaving said container free to move with respect to said valve to a position of register between said ash receiving opening and said discharge opening, and said mounting means and said container having releasably interlocking portions for releasably securing said container on said mounting means, said interlocking portions being arranged in predetermined aligned relation with said cooperating means to prevent removal of said container from said mounting means except when said container and valve are in relative positions fully closing said ash receiving opening.

3. Ash receiving apparatus for use with an

ash conveyor having a discharge opening in the upper part thereof, comprising a container having an ash receiving opening in the bottom thereof, a funnel mounted within said container with the lower end thereof in communication with said ash receiving opening, a valve for controlling said ash receiving opening, means connecting said valve and said container for relative rotation to open and close said ash receiving opening, means for mounting said container above said conveyor to receive ashes through said ash receiving opening from said discharge opening, means for locating and holding said valve in predetermined position out of the path of ashes discharged from said discharge opening, and means guiding said container for rotation relative to said mounting means and said valve to effect opening and closing of said ash receiving opening.

20 4. Ash receiving apparatus for use with an ash conveyor having a discharge opening in the upper part thereof, comprising a container having an ash receiving opening in the bottom thereof at a position eccentrically disposed with respect to the central axis of said container, said ash receiving opening being of substantially the same dimensions as said discharge opening, a valve supported by said container for rotation relative thereto about said central axis, said valve having an eccentrically disposed opening therethrough adapted to be brought into and out of registry with said ash receiving opening to open and close said ash receiving opening, means for mounting said container above said conveyor to receive ashes through said ash receiving opening from said discharge opening, means for locating said valve in predetermined position with respect to said conveyor wherein said valve opening is in register with said discharge opening, and means guiding said container for rotation with respect to said mounting means and said valve to bring said ash receiving opening into and out of register with said valve opening and said discharge opening.

45 5. Ash receiving apparatus for use with an ash conveyor having a discharge opening in the upper part thereof, comprising a container having an ash receiving opening in the bottom thereof at a position eccentrically disposed with respect to the central axis of said container, a funnel mounted within said container with the lower end thereof in communication with said ash receiving opening, a valve supported by said container for rotation relative thereto about said central axis, said valve having an eccentrically disposed opening therethrough adapted to be brought into and out of registry with said ash receiving opening to open and close said ash receiving opening, means for mounting said container above said discharge opening for rotary movement with respect to said conveyor about said central axis, means for keying said valve to said conveyor to align said valve opening with said discharge opening and to prevent rotary movement of said valve with respect to said mounting means, and interlocking means on said container and said mounting means preventing removal of said container from said mounting means except when said container and valve are in relative positions closing said ash receiving opening.

6. Ash receiving apparatus for use with an ash conveyor having a discharge opening in the upper part thereof, comprising a container having an ash receiving opening in the bottom thereof, means depending from said container

bottom to form a track, a valve rotatably mounted on said track and having an opening therethrough adapted to move into and out of register with said ash receiving opening to open and close said ash receiving opening, means for mounting said container above said conveyor to receive ashes through said ash receiving opening from said discharge opening, said mounting means and said track forming means having cooperating parts releasably locking said container and said mounting means together, means for keying said valve and said mounting means together to prevent relative rotation thereof, and stop means carried by said container and said mounting means for controlling relative rotation of said container and said mounting means to define limit positions of such rotation wherein said ash receiving opening is respectively fully opened and fully closed.

7. Ash receiving apparatus for use with an ash conveyor having a discharge opening in the upper part thereof, comprising a container having an ash receiving opening in the bottom thereof, a funnel mounted within said container with the lower end thereof in communication with said ash receiving opening, a valve for controlling said ash receiving opening, means connecting said valve and said container for relative rotation to open and close said ash receiving opening, means for mounting said container above said conveyor to receive ashes through said ash receiving opening from said discharge opening, means for keying said valve to said mounting means to locate and hold said valve in predetermined position out of the path of ashes discharged from said discharge opening, means guiding said container for rotation on said mounting means with respect to said valve to bring said ash receiving opening into and out of register with said discharge opening, stop means defining limit positions of such rotational movement wherein said ash receiving opening is respectively fully opened and fully closed with respect to said discharge opening, and interlocking means on said mounting means and said container preventing removal of said container from said mounting means except when said ash receiving opening is fully closed.

8. Ash receiving apparatus for use with an ash conveyor having a discharge opening in the upper part thereof, comprising a container having an ash receiving opening in the bottom thereof, a ring supported in spaced depending relation with said container bottom, a valve rotatably supported on said ring and having an opening therethrough adapted to be brought into and out of register with said ash receiving opening to open and close said ash receiving opening, means for mounting said container above said conveyor to receive ashes through said ash receiving opening from said discharge opening, means for keying said valve to said mounting means to locate said valve in predetermined position wherein said valve opening is in register with said discharge opening, projections on said mounting means adapted to overlap said ring for releasably securing said container and mounting means together, said ring having slots in the outer periphery thereof to receive said projections, stop means on said container cooperating with said projections to define limit positions of rotational movement of said container wherein said ash receiving opening is respectively fully in register with said discharge opening and fully closed by said valve, said slots in said ring being so located with relation to said stop means that said container can be removed from said mounting means only when said ash receiving opening is fully closed by said valve.
